WELL TOOL CONSTRUCTION

Jesse C. Wright, Los Angeles, and John B. Ragsdale, Whittier, Calif., assignors to Globe Oil Tools Company, Los Nietos, Calif., a corporation of California

Application January 4, 1933, Serial No. 650,132

3 Claims. (Cl. 255—72)

This invention relates to a well tool construction and relates more particularly to a construction or combination for embodiment in well drills, well core drills, and the like.

5 The various classes of well drills in general use in the rotary method of well drilling are relatively slow in their cutting action or penetration of the earth formation, as they usually involve cutting parts at or adjacent their axes of rotation which move comparatively slowly during rotation of the drills and thus retard their cutting action. Core drills are employed in well drilling operations to obtain cores or samples of earth formations in the wells. Core drills 10 usually embody a bit head for making an annular cut in the formation, a barrel for receiving the core cut by the bit head, and core retaining means for retaining the core in the barrel. The core retaining means of a core drill is commonly 15 placed adjacent or immediately above the bit head so that the length of the core receiving barrel is limited by the amount or length of the core that can be conveniently handled in one piece at the surface of the ground. Thus the 20 usual core drills, while they do not have cutting parts adjacent their axes of rotation, are not capable of or adapted to penetrate the formation for any considerable distance without being pulled or withdrawn from the well, and therefore 25 are not generally used as drilling tools or bits. Further, the amount of core or sample obtained by the core drill is limited by the length of the core receiving barrel and by the extent or length 30 of a single core that can be conveniently handled 35 at the surface.

It is an object of the present invention to provide a construction for embodiment in a core drill or in a well bit making an annular cut in a formation whereby the core drill or bit is capable of receiving and effectively handling a core or cores of great length so that the tool may be employed to penetrate or drill through the formation for a considerable or unlimited distance without requiring withdrawal from the 45 well.

It is another object of the invention to provide a core receiving barrel for embodiment in or application to a core drill or well bit that is adapted to effectively receive and retain cores 50 of great or unlimited length.

It is another object of the invention to provide a jointed or sectional core receiving barrel provided with a plurality of longitudinally spaced core retaining or supporting means whereby the 55 barrel may be taken apart at the surface of the

ground and sections of the core of convenient length will remain in the several sections or parts of the barrel.

It is another object of the invention to provide a core retaining and supporting means embodied in or provided on a member adapted to be connected between two parts or sections of a core barrel as a coupling for detachably connecting the sections of the barrel.

It is another object of the invention to provide core retaining and core supporting units of the character just mentioned that are extremely simple and inexpensive of manufacture and that are particularly effective and dependable in operation.

It is another object of the invention to provide core retaining units or coupling structures of the character mentioned that may be embodied in bits or core drills having a single body or barrel as well as in a coring outfit or core drill having an inner barrel structure within the outer barrel or body for receiving the core.

It is another object of the invention to provide a simple compact core retaining or holding unit including an assembly of one or more 25 core engaging dogs, bearing means for the dogs, and means for urging the dogs into engagement with the core which assembly is in the form of a unit that may be mounted or assembled with ease.

Other objects and features of the invention will be better and fully understood from the following detailed description of typical forms and applications of the invention, throughout which description reference is had to the accompanying drawings in which:

Fig. 1 is a side elevation of a well tool embodying the construction provided by the invention. Fig. 2 is an enlarged side elevation and partial vertical section of the tool illustrated in Fig. 1. Fig. 3 is an enlarged transverse detailed sectional view taken as indicated by line 3—3 on Fig. 2. Fig. 4 is an enlarged side elevation of one of the core engaging dogs included in the form of the invention illustrated in Figs. 1, 2 and 3. Fig. 5 is a bottom view of the dog illustrated in Fig. 3. Fig. 6 is an enlarged perspective view of one of the blocks for carrying the core engaging dogs. Fig. 7 is a transverse detailed sectional view of another form of core engaging or retaining unit, being a view taken as indicated by line 7—7 on Fig. 8. Fig. 8 is a side elevation and partial vertical section of the modified or alternate form of core retaining unit. Fig. 9 is an enlarged perspective view of one of the blocks included in the form of

core retaining unit illustrated in Figs. 7 and 8. Fig. 10 is a longitudinal detailed sectional view of another form of core drill embodying the present invention.

5. In accordance with its broader aspects the invention is adapted to be embodied in or used in connection with bits and well core drills of various characters. The invention may be applied to or included in a bit or core drill having a single 10 body or barrel, or in a bit or core drill having an outer tubular body and an inner core receiving barrel. Throughout the following detailed disclosure we will describe typical preferred forms of the invention embodied in a typical single barrel 15 bit or core drill and in a typical double or two barrel core drill. It is to be understood that the present invention is not to be construed as limited or restricted to the specific forms or embodiments about to be described, or to use in connection with 20 the particular classes of tools illustrated in the drawings, but is to be taken as including any features or modifications that may fall within the scope of the claims.

The tool illustrated in Figs. 1, 2 and 3 of the 25 drawings, embodying one form of the present invention, includes generally, a bit head 10 for making an annular cut in the formation, a sectional tubular body or barrel 11 carrying the bit head 10, and a plurality of spaced core retaining units 30 12 connected or assembled in the core receiving barrel 11.

The present invention is not primarily concerned with the specific construction of the bit head 10 and we have illustrated a bit head of the 35 character described and claimed in the co-pending application for Letters Patent of J. H. Howard and A. C. Catland entitled Bit head, Serial No. 650,131, filed January 4, 1933, including a tubular body or shoe 13 and cutting parts 14 on the shoe. The shoe 13 of the bit head is provided at its 40 upper end with suitable means for connecting with the core receiving barrel. The shoe of the particular bit head 10 illustrated in the drawings has a tapered screw threaded socket 15 in its upper end to facilitate connection with the barrel 11. The vertical or longitudinal opening 16 of the shoe 13 is adapted to pass the core or cylindrical 45 part of the formation made by the cutters 14 upwardly into the barrel 11. The lower end portion of the opening 16 may be restricted as illustrated in Fig. 2 of the drawings so that the core has desirable clearance when received by the barrel 11 and so that the circulation fluid is discharged at an increased velocity about the core as it enters 50 the bit head. The cutting parts 14 are in the nature of substantially radial blades projecting downwardly and outwardly from the lower end portion of the shoe 13. There is a suitable number of circumferentially spaced cutting blades 14, 55 each provided with a lower cutting edge 17, a side reaming edge 18, and a core shaping or trimming edge 19.

The core receiving barrel 11 and the assembly 60 of the barrel 11 and the core retaining units 12 are important features of the present invention. The barrel 11 is adapted to be attached to the lower end of an operating string of drill pipe, or the like, for example, it may be attached to a 65 drill collar on the lower end of an operating string. In accordance with the invention, the barrel 11 is sectional, and may be of any suitable or desired length. The core receiving barrel 11 includes a plurality of elongate tubular sections 70 20. There may be any desired number of sections 20 embodied in the barrel 11, it being ap-

parent that the length of the barrel is determined by the length and number of the sections 20 embodied in the structure. The tubular barrel sections 20 are of like diameter and are preferably of greater internal diameter than the bit head 10 so that the core may pass into the barrel with clearance and without binding or jamming. It is a feature of the invention that the tubular barrel sections are detachably connected together and that the lowermost section 20 is detachably 10 connected to the bit head 10 through the core retaining units 12 as will be subsequently described. Means is provided at the upper end of the barrel 11 to facilitate connection with the lower end of the drilling string. In the particular case illustrated in the drawings, a sub 21 is attached to the upper end of the upper section 20 of the barrel and is provided with a tapered threaded pin 22.

The core retaining units 12 are provided to retain and support the core within the barrel 11. 20 In practice, where the tool is used as a drilling bit in relatively soft earth formations, the circulating fluid under pressure passing downwardly through the barrel 11 may erode or wash away the softer parts of the core or formation that 25 enters the bit head opening 16 and the barrel 11 so that only the harder or more resistant portions of the core remain in the barrel to be retained by the units 12 when the tool is withdrawn from the well. Where the tool is used primarily as a core 30 drill for obtaining samples of the earth formation, the conditions of operation may be such that substantially the entire core is retained intact within the barrel 11 and is supported and held in the barrel by the core retaining units 12. As the tool 35 embodies only a single tubular body or barrel it is operable to obtain a core considerably larger in diameter than cores taken by the usual two barrel drills, and as the barrel 11 may be of great length and is provided at spaced points with the core retaining units 12, a very long core may be 40 taken if desired.

The core retaining units 12 are arranged or connected between adjacent ends of the several sections 20 of the barrel and one or more units 12 may be arranged or connected between the bit head 10 and the lower end of the lowermost barrel section 20. In accordance with the form of the invention being described, the units 12 are 45 in the form of couplings or connections for connecting the several barrel sections 20 and for connecting the barrel 11 and the bit head 10.

The number of core retaining units 12 included in the tool depends upon the length of the barrel 11 or the number of sections 20 included in the 50 barrel and upon the spacing of the units. The several core retaining units 12 may be alike in construction to simplify the assembly. Each unit 12 includes a tubular body 25 having means at its opposite ends for connecting with adjacent 55 portions of the tool assembly. The bodies 25 of the units 12 may resemble subs and may have comparatively heavy or thick walls. The openings 26 in the unit bodies 25 may be of substantially the same diameter as the major portion 60 of the bit head opening 16. In accordance with the broader principles of the invention, the bodies 25 of the core retaining units 12 may be connected to or with the adjacent ends of the barrel sections 20 in any suitable or practical manner. In the 65 case illustrated in the drawings adaptor subs 26 are screw threaded on the lower end of the barrel sections 20 and are provided at their lower ends with tapered pins 27 having comparatively coarse threads. The upper ends of the unit 70 75

bodies 25 are provided with tapered sockets 28 having coarse threads for cooperating with the threads of the pins 27. The lower ends of the unit bodies 25 may be connected with the upper 5 ends of the adjacent barrel sections 20 through lower adaptor subs 29. The subs 29 may be threaded to the upper ends of the barrel sections 20 in the usual manner and have threaded connections with the unit bodies 25. In the particular assembly illustrated in the drawings, a coarsely threaded pin 30 is provided on the lower end of each body 25 to thread into a socket 31 in the upper end of an adaptor sub 29. From the above 10 description of the bodies 25 of the core retaining units 12 and the typical means for connecting them in the barrel assembly, it will be apparent that the invention provides a simple sectional core receiving barrel in which the principal tubular sections 20 are connected together through 15 the bodies 25 and suitable connecting members or adaptor subs.

One or more core gripping and retaining dogs 32 or sets of core retaining dogs 32 are provided on each unit 12. In the typical form of the invention disclosed in the drawings there are four 20 sets of two dogs 32 carried by the body 25 of each unit 12. The core gripping and retaining dogs 32 are carried or supported by blocks 33 secured in openings or vertically elongated slots 34 in the 25 walls of the bodies 25. Where the units 12 embody four sets of core retaining dogs 32 there are four circumferentially spaced vertically elongated slots 34 provided in each body 25. The blocks 33 are rectangular or elongate and fill the slots 34. 30 The blocks 33 may project slightly from the exteriors of the bodies 25 and may be secured in the slots 34 in any suitable manner, for example, they may be welded to the bodies 25. Two vertically spaced pockets or recesses 35 are provided in the inner side of each block 33. The recesses 35 may extend through the blocks 33 from one vertical side of a slot 34 to the other. The recesses 35 are shaped to receive the major portions of the gripping dogs 32 when the core is passing into the barrel 11 and to effectively support the dogs 32 when the dogs are carrying the core. Each recess 35 has a downwardly and outwardly inclined upper wall 36 and a flat lower wall 37. A concaved cylindrically curved or rounded seat 38 joins the walls 36 and 37 of each recess 35.

The dogs 32 for retaining and supporting the core within the barrel 11 are pivoted in the recesses 35 and project from the interiors of the unit bodies 25 to engage and bite into the core. 40 A transverse or horizontal opening 39 is provided in each dog 32 adjacent its lower end. Tubes 40 extend through the openings 39 and washers 41 are provided on the opposite projecting end portions of the tubes. The opposite ends of the tubes 40 may be spread or flared slightly to retain the washers 41 on the tubes and in engagement with the sides of the dogs 32. Vertical longitudinal cuts or slits 42 are provided in the lower ends of the dogs 32 to intersect the tube carrying openings 39. Torsional springs 43 are carried by or wrapped about the tubes 40 within the slits 42. One end of each torsional spring 43 is held in a reduced opening or socket 44 in a dog 32, while the opposite ends of the springs engage the walls of the recesses 35 whereby the springs 43 normally urge the dogs 32 into the openings 26 to engage the core. Tangential openings 46 are provided in the unit bodies 25 and intersect the slots 34. Suitable pins 47 are arranged in the 45 openings 46 to pass through the tubes 40 of the

dogs 32 and pivotally support the dogs in the recesses 35. The pins 47 may have socketed or slotted heads threaded into the outer ends of the openings 46.

The dogs 32 each have a flat upper side 48 adapted to lie against the upper inclined wall 36 of a recess when the core is passing into the barrel and has a flat lower surface 49 which is adapted to seat on the lower wall 37 of a recess when the dog is in supporting engagement with the core. The inner ends of the core engaging dogs 32 are cylindrically rounded or curved about their pivotal axes and bear or pivotally fit into seats 38. The seating of the inner ends of the dogs 32 against the seats 38 and the engagement of the lower sides 49 of the dogs with the bottoms of the recesses 35 provides for the direct transmission of the weight of the core from the dogs to the blocks 33.

The outer ends of the dogs 32 which project 20 into the openings 26 are shaped and proportioned so as to effectively cut or bite into the core. The outer end portions of the dogs 32 are reduced in thickness and the extreme ends of the dogs are bevelled to terminate in edges 50. During operation of the tool when the drill is passing downwardly into the formation and the core is being received by the barrel 11, the pivoted dogs 32 engage the core and are held in the up and out positions, illustrated in Fig. 2 of the drawings, by 25 the downward movement of the tool relative to the core. When the tool is raised to remove it and the core from the well, the sharpened outer ends of the dogs 32 bite into the core so that the dogs are pivoted downwardly through the relative movement between the barrel and core and thus bite into the core to retain it in the barrel and if necessary, to break it loose from the formation. In hard formations, it may be necessary to rotate the drill while raising it so that the dogs 30 32 make annular cuts in the core to assume their core retaining positions and/or to break the core loose from the formation in the bottom of the well bore. The washers 41 effectively space the opposite sides of the dogs 32 from the end walls 45 of the recesses 35 and operate as thrust bearings or washers.

It is believed that the utility and operation of the tool illustrated in Figs. 1, 2 and 3 of the drawings will be readily apparent from the foregoing 50 detailed description. In operation, the drill may be operated in the usual manner, that is, it may be rotated to cause the bit head 10 to make an annular cut in the formation. The core cut by the bit head 10 passes into the barrel 11 as the 55 tool advances through the earth formation. Where the tool is operated as a drill or bit, the circulation of fluid through the tool may be such as to wash away or erode the softer portions of the core while the more resistant components 60 of the core remain in the barrel 11. When the tool is used as a core drill for obtaining samples of the formation, the entire core may be received and retained with the barrel 11. During the passage of the core into the barrel 11, the dogs 65 32 are in their up and out positions illustrated in Fig. 2 of the drawings so that they do not materially interfere with the core, but maintain engagement with the core through the pressure of the torsional springs 43. When the tool is 70 raised or pulled upwardly the sharpened ends 50 of the dogs bite into the core causing the dogs to pivot downwardly in the recesses 35 and penetrate the core for considerable distances. The core may be broken away from the formation 75

either by a straight up pull or by rotation of the tool during the up pull which causes the dogs 32 to make annular cuts in the core so that it may be broken from the formation at the lower 5 core retaining unit 12. As the core barrel 11 may be extremely long a very long core may be obtained and the provision of the core retaining units 12 at longitudinally spaced points insure the proper retention and supporting of the core 10 or sections of the core within the barrel. As the barrel 11 provided with the core retaining units 12 is adapted to receive and retain a core of unlimited length, the tool is operable to cut through the formation for an extensive distance and if 15 desired, may be employed as a drilling bit as well as a means for obtaining samples of the formation in the bore.

When the tool has been withdrawn from the well and it is desired to inspect the core within 20 the barrel 11, the barrel 11 may be taken apart either immediately above or immediately below the units 12, that is, the unit bodies 25 may be disconnected from either the adaptor subs 26 or 25 29 so that the portions of the core within the body sections 20 may be easily removed in lengths that may be conveniently handled. The tool involving only a single barrel and in being of moderate wall thickness is operable to obtain cores of large diameter. The core retaining units 12 30 in detachably connecting the adjacent ends of the barrel sections 20 provides for the quick and easy separation or disconnection of the barrel sections and insure the proper supporting of the core within the barrel at suitably spaced points. 35 The core retaining units 12 are simple and inexpensive of manufacture, consisting of the simple tubular bodies 25 and the sturdy effective dogs 32 supported in the blocks 33. The springs 43 in being carried on the tubes 40 40 allow the assemblies of the dogs, tubes, and springs to be easily and quickly mounted in the recess 35 as units. It will be apparent that in some constructions and under certain conditions it may be desirable to merely attach or retain the core retaining units 12 between connected parts of the barrel.

Figs. 7, 8 and 9 of the drawings illustrate a modified or alternate form of core retaining unit adapted to be connected or arranged in a core receiving tube or barrel in the same manner as the units 12 described above. The core retaining unit illustrated in Figs. 7, 8 and 9 of the drawings includes a body 55 and one or more core gripping slips 56 operable in the body.

The body 55 may be in the nature of a coupling or connecting member adapted to connect together parts of a well tool, for example, two tubular sections of a core receiving barrel. The unit body 55 may be similar to one of the bodies 25 described above, that is, it may be provided at its opposite ends with suitable connecting means. In the case illustrated, a tapered screw threaded socket 57 is provided in the upper end of the body 55 while a tapered threaded pin 58 is provided on the lower end of the body. The longitudinal opening 59 of the body 55 may be of uniform cross section throughout its length. In accordance with this embodiment of the invention the body 55 is provided with one or more vertically elongated openings or slots 60. The particular form of the invention being described involves four core engaging slips 56 and four equally spaced slots 60 are provided in the walls of the body 55. A block 61 is provided in the outer 70 end portion of each slot 60. The blocks 61 may

be welded or otherwise attached to the body 55 and their exteriors may be substantially flush with the exterior of the body. The inner sides 62 of the blocks are inclined downwardly and inwardly to form surfaces for slidably supporting the slips 56. The outer portions of the slots 60 are of enlarged horizontal cross section so that shoulders 63 are provided in the side walls of the slots. The shoulders 63 are inclined downwardly and inwardly being of the same inclination as the inner sides 62 of the blocks 61. The blocks 61 fit the slots 60 so that their inner sides 62 are spaced from the shoulders 63 to provide inclined key-ways 64 in the slip carrying portions of the slots 60. The provision of the inclined key-ways 64 makes the slip carrying slots 60 substantially T shaped in horizontal cross section.

The core engaging slips 56 are slidable vertically or longitudinally in the T shaped slots 20 just described. There may be one slip 56 in each slot 60. The outer sides 65 of the slips 56 are inclined to slidably cooperate with the inner sides 62 of the blocks 61 and the slips are substantially T shaped in cross section having laterally 25 projecting inclined keys 66 slidably fitting the key-ways 64. Upward movement of the slips 56 is limited by the upper ends of the slots 66 while blocks or bars 67 limit the downward movement of the slips. The bars 67 extend across the 30 lower end portion of the slip carrying slots 60 and may be counter-sunk in the inner faces 62 of the blocks 61. Screws 68 pass through openings in the blocks 61 and thread into the bars 67 to detachably retain the bars in position. The removable bars 67 prevent detachment or displacement of the slips 56 from the units and may be removed to take the slips 56 out of the slots. The inner ends of the slips 56 are provided with one or more upwardly inclined teeth or core biting parts 69. The slips 56 are proportioned so 35 that they project into the openings 59 when in the extreme up positions illustrated in Fig. 8 of the drawings so that they are at all times in engagement with the core extending through the 40 barrel and unit.

During downward passage of the tool into the earth formation the slips 56 are retained in their up positions through relative movement between the core and barrel. When the barrel is moved upwardly the slips 56 are held against upward movement through their engagement with the core and the inclined faces 62 and keyways 64 force the slips inwardly into tight gripping and holding engagement with the core. This engagement of the slips with the core is maintained during the removal of the tool from the well as the weight of the core supported by the slips retains the slips in their down and core holding positions. It will be apparent how the core retaining unit illustrated in Figs 7, 8 and 9 of the drawings may be readily embodied in various forms of core receiving barrels and how a plurality of these units may be connected between the several tubular sections of an elongate barrel of the class described above to act as detachable connecting means, as well as means for supporting the portions of the long core.

Fig. 10 of the drawings illustrates a form of the invention involving a core receiving means comprising core receiving tubular sections 70 arranged within the body or main barrel of the tool. The tool illustrated in Fig. 10 includes, generally, a bit head 70 for making an annular cut in the earth formation, a sectional body or barrel 71 carrying the bit head 70, a

plurality of core retaining or catching units 72 interposed or assembled in the barrel 71, and tubular core receiving sections 73 within the barrel 71.

5 Any suitable form of bit head may be used in connection with the tool construction illustrated in Fig. 10 of the drawings. The bit head 70 is a typical core drill bit head including a shoe, 74 and cutting parts 75. The shoe 73 is tubular, and is provided at its upper end with a threaded socket 76. The cutting parts 75 are in the nature of blades projecting downwardly and outwardly from the lower end of the shoe 73. The cutting blades 75 are circumferentially spaced on the shoe 15 74 and are operable to make an annular cut in the formation to pass the core drill with clearance.

The body or barrel 71 is an elongate tubular structure carrying the bit head 70 and adapted 20 to be attached to the lower end of an operating string of drill pipe, or the like. In accordance with the invention, the barrel 71 is sectional including a plurality of elongate tubular sections 77. The several sections 77 of the barrel 71 are connected together by the units 72, and the lowermost section 77 is connected with the bit head 70 by a unit 72, as will be hereinafter described.

25 The core catching or core retaining units 72 are assembled in the sectional barrel 71 and constitute means for connecting the several barrel sections 77. A core retaining unit 72 is connected between the adjacent ends of each of the several sections 77 and a unit 72 is arranged between the lower end of the lowermost section 30 77 and the bit head 70. Each core retaining unit 72 includes a body 78 in the form of a sub that is adapted to connect together two members of the tool. The bodies 78 of the core retaining units are tubular, having central longitudinal openings 79 and are provided at their 35 opposite ends with means for facilitating connection with other members of the assembly. In the typical form of the invention illustrated in the drawings, the upper end of each body 78 is provided with a threaded socket 79a and a threaded pin 80 is provided on the lower end of each body. A sub or connecting member 81 may be provided on the lower end of each barrel section 77. The connecting members 81 may have pins 82 threaded into the sockets 79a in the upper ends of the unit bodies 78. A connecting-member 83 may be threaded on the upper end of each barrel section 77 and may be provided at its upper end with a socket 84 for receiving a pin 80. The threaded pin 80 of the unit body 78 on the lower end of the lowermost barrel section 77 may be threaded directly into the socket 76 in the bit head 70. The openings 79 on the unit bodies 78 are of considerably less diameter than the openings of the barrel sections 77 and the walls of the bodies 78 are comparatively thick.

40 One or more core retaining elements 86 is carried by the body 78 of each unit 72. The core retaining elements 86 may be in the nature of pivoted dogs similar to the dogs 32 described above or may be in the nature of slips similar to the slips 56 illustrated in Figs. 7 and 8 of the drawings. In the particular embodiment of the invention being described, the core retaining elements 86 are in the nature of pivoted dogs carried by blocks 87 arranged in slots 88 in the walls of the unit bodies 78. The blocks 87 may be welded in the slots 88 as illustrated in the drawings. Recesses 90 are provided in the inner

5 sides of the blocks 87 to carry the outer ends of the dogs 86. There may be one or more pivoted dogs carried by each unit body 78. In the specific construction illustrated, there is a pair of dogs on each block 87 and a plurality of blocks 87 on each unit body 78. The blocks 87 are spaced apart circumferentially on the bodies 78, for example they may be spaced substantially 120° apart as illustrated in the drawings. The core retaining dogs 86 and their 10 mountings may be identical with the dogs 32 and the mountings for the dogs 32 described above, and reference may be had to the description of the dogs 32 to obtain a full understanding of the present embodiment of the invention. 15 The core retaining dogs 86 project into the openings 79 of the unit bodies 78 and their inner core engaging ends may be bevelled or sharpened.

20 The core receiving and holding sections 73 are provided to receive the core cut by the bit head 70 and to allow or provide for the circulation of circulating fluid downwardly through the tool without washing away the core. The sections 73 are elongate tubular members arranged with- 25 in the sections 77. One core receiving section 73 is arranged within each section 77 and the sections 73 are carried by or attached to the bodies 78. The sections 73 are of considerably less diameter than the sections 77 so that annular circulation passages 92 are provided between 30 the sections 73 and 77. The lower ends of the core receiving sections 73 are screw threaded into sockets 93 in the upper portions of the openings 79 of the unit bodies. The upper end por- 35 tions of the sections 73 have sliding connec- 35 tions or telescopic engagement with the bodies 78. Enlargements or sockets 94 are provided in the lower ends of the openings 79 to receive the upper end portions of the sections 73.

40 The form of the invention illustrated in Fig. 10 of the drawings includes means for circulating the circulation fluid downwardly through the assembly or tool to discharge from the bit head 74. The openings in the tubular connecting members 81 and 83 are sufficiently large in diameter to provide annular spaces or passages 96 around the core receiving sections 73 which passages 96 form continuations of the passages 92. Longitudinal fluid passages 98 are provided in the unit bodies 78 to connect the openings or 45 passages 96 in the connecting members on the opposite ends of the bodies. The passages 98 50 in the lowermost unit body 78 communicate with or discharge into an annular recess 99 in the upper end of the bit head shoe 74. Fluid discharge passages 100 are provided in the shoe 74 55 to communicate with the recess 99 and discharge from the lower end of the shoe.

60 The tool illustrated in Fig. 10 of the drawings is adapted to be operated on the lower end of a string of drill pipe, or the like, and the bit head 70 makes an annular cut in the formation providing a core which passes upwardly into the sections 73. During the passage of the core into the tool the dogs 86 are in the retracted positions illustrated. When the tool is raised to break the core from the formation and to pull the tool from the well, the dogs 86 pivot downwardly to bite into the core so that the core may be broken away from the formation and retained 65 in the sections 76. After the tool has been withdrawn from the well, the threaded connections or joints at the lower ends of the unit bodies 78 may be released or broken and the various parts above these connections may be lifted off of 70 75

both the inner sections 73 and the outer sections 71 below the disconnected joint. The core or sections of core contained within the sections 73 may then be removed by means of a plunger introduced into the lower ends of the sections. The tool illustrated in Fig. 10 of the drawings provides for the effective free passage of the circulation fluid to the bit head without in any way contacting with the core and is such that the core may 10 be easily and quickly removed from the section 73 by disconnecting the parts of the barrel 71 at the core retaining units 78.

Having described only a typical preferred form of our invention, we do not wish to limit ourselves to the specific details set forth, but wish to reserve to ourselves any changes or variations that may appear to those skilled in the art or fall within the scope of the following claims.

Having described our invention, we claim:

20 1. In a well tool, a tubular body having a recess in its inner wall, a dog having a transverse opening, a tube extending through the opening, a spring carried by the tube, the assembly of the dog, tube and spring being adapted to be 25 arranged in the recess as a unit, and a pin carried by the body and passing through the tube

to pivotally support the dog in the recess, the spring reacting between the body and dog to pivot the dog inwardly.

2. In a well tool, a tubular body having a recess in its inner wall, a dog having a transverse opening, and a slot intersecting the opening, a spring in the slot carried by the tube, the assembly of the dog, tube and spring being adapted to be arranged in the recess as a unit, and a pin on the body extending through the tube to 10 pivotally support the dog in the recess, the spring reacting between the body and dog to pivot the dog inwardly.

3. In a well tool, a barrel for receiving a core and comprising a plurality of lengths of tubing, 15 and means connected between the lengths of tubing for retaining a core in the barrel, each of the said means including a tubular body having a slot in its wall, means at the opposite ends of the body for connecting with the barrel, a block 20 fixed in the slot and having spaced recesses in its inner side, and a core engaging element pivoted in each recess and adapted to project from the interior of the body.
